US0D1111935S

(12) United States Design Patent (10) Patent No.: US D1,111,935 S
(45) Date of Patent: * Feb. 10, 2026

(54) BICYCLE

(71) Applicant: Washington Adhemar Perez Igiel,
Buenos Aires (AR)

(72) Inventor: Washington Adhemar Perez Igiel,
Buenos Aires (AR)

() Term: 15 Years

(21) Appl. No.: 29/920,790

(22) Filed: Dec. 13, 2023

(30) Foreign Application Priority Data

Jun. 15, 2023 (AR) 104006

(51) LOC (15) Cl. 12-11

(52) U.S. Cl.

USPC D12/111

(58) Field of Classification Search
